SULFONIC ACID ESTERS OF 2-DIALKYLAMINE ETHANOLS

James M. Sprague, Drexel Hill, and Edward L. Engelhardt, Collingdale, Pa., assignors to Merck & Co., Inc., a corporation of New Jersey

No Drawing. Application February 8, 1950,
Serial No. 143,164

6 Claims. (Cl. 260—456)

This invention relates to new esters of 2-dialkylaminoethanols, and more particularly to compounds having the following general structural formula:

In this compound R' and R'' may be selected from a wide variety of alkyl, aralkyl and aryloxyalkyl radicals. The exact character of R' and R'' is not critical other than that between them they contain at least one and preferably two benzene rings, which must be linked to the nitrogen through a chain of at least one and no more than two aliphatic carbon atoms. The benzene rings may be attached directly to the aliphatic carbon chain or the linkage may be through an oxygen or sulfur atom, provided that said aliphatic carbon chain consists of two carbon atoms. When two benzene rings are present, they may be linked to the nitrogen through the same alkyl chain or through separate alkyl chains, or they may together form a polycyclic aromatic nucleus, or one benzene ring may be linked to the other through an aliphatic carbon atom. Both R' and R'' must be organic radicals and neither can be hydrogen.

In the known compounds of this type, X is a halogen such as chlorine. Representative compounds, when X is a halogen and R' and R'' are as above set forth, are illustrated in the article, "The Chemical Basis for Adrenergic Blocking Activity in Compounds Related to Dibenamine," by Mark Nickerson and William S. Gump, The Journal of Pharmacology and Experimental Therapeutics, vol. 97, No. 1, September, 1949, page 25.

When the free base is dissolved in a polar solvent, an explanation has been advanced that what occurs is that the compound undergoes an internal cyclization to form the following ions:

To determine the rate at which cyclization occurs, the rate of formation of the cyclized ion is measured by the rate of reaction of the compounds of general structure (1) with sodium thiosulfate. This reaction appears to take place according to the following sequence:

The rate of cyclization is the rate determining step of the over-all reaction. To determine the relative rates of formation of the cyclized ion, therefore, it is merely necessary to add the 2-dialkylaminoethanol derivative to a solution containing sodium thiosulfate and to detect the rate of decrease of the sodium thiosulfate.

In the case of the known compounds, in which X is a halogen such as chlorine, the rate of this cyclization is

2

quite slow. Thus, for 75% cyclization to occur when the base is dissolved in dilute alcohol, from 20 to 90 minutes is required at room temperature.

In accordance with the present invention, it has been discovered that if the X radical of the compound is a sulfonic acid radical, the rate of cyclization is very unexpectedly increased, and is too rapid to be measured readily at room temperature. At 5° C. the cyclization is 75% complete within 5 to 30 minutes.

10 This rapid rate of cyclization of the compounds of the invention is of particular importance when the material is used as a therapeutic agent. When the compounds have as X a halogen, the therapeutic response is relatively slow and this is no doubt due to the slow rate of cyclization. In contrast to this, due to the extremely rapid rate of cyclization of the sulfonic acid ester, a more rapid therapeutic response results.

15 The reason for the extremely rapid cyclization of the compounds of the invention is not understood. It would be expected that such a marked difference as is observed would not occur merely by the substitution for the halogen radical of a sulfonic acid ester radical.

20 The compounds of the invention, that is, those in which X is a sulfonic acid ester, may therefore be represented by the formula:

25 30 The R substituent may be any lower alkyl radical up to eight carbon atoms and it may be either straight or branched chain. Or R may be aryl or aralkyl such as phenyl, p-tolyl or benzyl, or aryloxyalkyl such as phenoxyethyl. Representatives of these organic radicals will be apparent from the subsequent examples.

35 40 The substituents R' and R'' of the compounds of the invention may be selected from the class defined above, and more specifically illustrated in the aforementioned article by Nickerson and Gump. The exact character of R' and R'' is not critical in the present invention within this class of radicals, inasmuch as the invention is primarily concerned with the sulfonic acid ester character of the substituent X. It may be observed that an ethylene radical is present between the ester, oxygen and nitrogen constituents of the compound. Either of these two carbons may bear, instead of hydrogen atoms, substituents such as lower alkyl radicals without materially impairing the desired cyclization or the intended results of the invention.

45 50 To obtain the compounds of the invention it is possible to follow several different procedures. For example, the hydrochloride of a dialkylaminoethyl chloride may be treated with the silver salt of the selected sulfonic acid according to the following scheme:

55 60 In practice the reactants are dissolved in a polar non-hydroxylic solvent such as a lower alkyl cyanide, for example, methyl cyanide. The mixture should be heated for a period from 1 to 3 hours at a temperature of from 60° to 100° C. At the end of this time the mixture is cooled and the precipitated silver chloride separated. The sulfonic acid ester of the 2-dialkylaminoethanol is recovered in the form of its sulfonic acid salt by evaporating the solvent.

Another method by which the products of the invention may be obtained is by treating the dialkylaminoethanol with the anhydride of the selected sulfonic acid, as illustrated by the following:

In carrying out this reaction the ingredients may be mixed together in the presence of a solvent such as benzene, chloroform, or ether and the mixture allowed to stand at room temperature for a period of 3 to 15 hours, or the solution may be heated to refluxing for an hour. The desired sulfonic acid ester is obtained in the form of its sulfonic acid salt by evaporating the solvent.

Somewhat higher yields are obtained if the dialkylaminoethanol is treated with the alkanesulfonic anhydride in the presence of a lower alkyl cyanide such as methyl cyanide as a solvent. This reaction may be carried out at room temperature for a period of from 3 to 15 hours or at reflux temperature for an hour. To recover the desired product, the isolation procedure mentioned above may be carried out.

The invention will be further illustrated by reference to the following examples:

Example I

2-dibenzylaminoethyl chloride hydrochloride, 2.96 g. (0.01 mole) and silver methanesulfonate, 4.06 g. (0.02 mole) were dissolved in 75 ml. of dry acetonitrile. The solution was stirred mechanically and heated to refluxing for three hours in an apparatus protected from moisture. The precipitate of silver chloride which had formed during the course of the reaction, was separated by filtration and the clear filtrate evaporated at 55-60° C. under reduced pressure. The residue, consisting of the methanesulfonic acid salt of 2-dibenzylaminoethyl methanesulfonate, was obtained in a yield of 95%. The purity of the product was estimated by titration against sodium thiosulfate in dilute alcohol as solvent, using essentially the method of Golumbic, Fruton and Bergmann, J. Organic Chem. 11, 522 (1946). It was 94% pure.

Example II

By substituting the chemically equivalent quantity of silver ethanesulfonate for the silver methanesulfonate of Example I and following the procedure of Example I, the ethanesulfonic acid salt of 2-dibenzylaminoethyl ethanesulfonate was obtained as a gum in 92% yield. The product was 91% pure.

Example III

By substituting the chemically equivalent quantity of silver 2-propanesulfonate for the silver methanesulfonate of Example I and following the procedure of Example I, the 2-propanesulfonic acid salt of 2-dibenzylaminoethyl 2-propanesulfonate was obtained in 97% yield in the form of an opalescent syrup which hardened to a resin on cooling. The product was 95% pure. It crystallized when triturated with 50% propylene glycol containing 0.5 mole per liter of 2-propanesulfonic acid.

Example IV

The process of Example I was carried out but substituting the chemically equivalent amount of silver n-hexanesulfonate for the silver methanesulfonate. From this was obtained the n-hexanesulfonic acid salt of 2-dibenzylaminoethyl n-hexanesulfonate.

Example V

2-dibenzylaminoethyl chloride hydrochloride, 1.48 g. (0.005 mole) and silver α -toluenesulfonate, 2.79 g. (0.01 mole) were dissolved in 50 ml. of dry acetonitrile. The solution was stirred mechanically and heated to refluxing for 3 hours, then cooled and the precipitate of silver

chloride separated by filtration. The filtrate was evaporated at 55-60° C. under reduced pressure. The residue, the α -toluenesulfonic acid salt of 2-dibenzylaminoethyl α -toluenesulfonate was obtained in 97% yield as a colorless resin. The product was 92% pure.

Example VI

p-Toluenesulfonic anhydride, 6.53 g. (0.02 mole) was dissolved in 60 ml. of dry acetonitrile by warming. The solution was cooled to 25° C. and a solution of 4.83 g. (0.02 mole) of dibenzylaminoethanol in 25 ml. of dry acetonitrile, added dropwise while stirring the reaction mixture. The toluenesulfonic anhydride began to separate shortly after the addition of the amino alcohol was begun.

The reaction mixture was heated to 38° C. when it became homogeneous, and maintained at this temperature during the remainder of the addition. The clear, homogeneous solution was allowed to stand overnight at room temperature, then heated to refluxing for 1 hour. The reaction mixture then was cooled, and the product, the p-toluenesulfonic acid salt of 2-dibenzylaminoethyl p-toluenesulfonate, isolated by fractional precipitation with absolute ether. A portion of the middle fraction was dissolved in absolute methanol by warming cautiously. The solution was diluted with absolute ether to incipient cloudiness, seeded and chilled. The purified white crystalline product melted at 144-146° C. Recrystallization did not change the melting point.

Anal.—Calcd. for $\text{C}_{22}\text{H}_{25}\text{O}_3\text{NS} \cdot \text{C}_7\text{H}_8\text{O}_3\text{S}$: C, 63.47; H, 5.86; N, 2.47. Found: C, 62.61; H, 5.93; N, 2.45.

The product assayed 101.6% by titration against sodium thiosulfate.

Example VII

2-Dibenzylaminoethyl chloride hydrochloride, 2.96 g. (0.01 mole) and silver p-toluenesulfonate, 5.58 g. (0.02 mole) were dissolved in 75 ml. of dry acetonitrile. The solution was heated to refluxing while stirring for 3 hours, then cooled and the precipitate of silver chloride separated by filtration. The solvent was evaporated at 55-60° C. under reduced pressure and the residue dissolved in 75 ml. of absolute methanol by warming slightly. After filtering the solution to remove a trace of silver chloride, it was diluted with 100 ml. of absolute ether and chilled. The white crystalline product, the p-toluene-sulfonic acid salt of 2-dibenzylaminoethyl p-toluenesulfonate, M. P. 144-146° C., was obtained in a yield of 71%. Recrystallization did not change the melting point.

Anal.—Calcd. for $\text{C}_{22}\text{H}_{25}\text{O}_3\text{NS} \cdot \text{C}_7\text{H}_8\text{O}_3\text{S}$: C, 63.47; H, 5.86; N, 2.47. Found: C, 62.65; H, 5.93; N, 2.42.

This product assayed 102% by titration against sodium thiosulfate.

Example VIII

The reaction of Example VII was carried out but substituting the chemically equivalent amount of silver benzenesulfonate for the silver p-toluenesulfonate. From this was obtained the benzenesulfonic acid salt of 2-dibenzylaminoethyl benzenesulfonate.

Example IX

Methanesulfonic anhydride, 3.61 g. (0.0207 mole) was dissolved in 50 ml. of dry benzene. A solution of 5.00 g. (0.0207 mole) of 2-dibenzylaminoethanol in 25 ml. of dry benzene was added and the clear solution allowed to stand overnight at room temperature. The solvent was evaporated at 55-60° C. under reduced pressure and the residue dried at 60° (1 mm.). The product, the methanesulfonic acid salt of 2-dibenzylaminoethyl methanesulfonate was 71% pure.

Example X

2-Dibenzylaminoethanol, 5.00 g. (0.0207 mole), dissolved in 30 ml. of dry acetonitrile was added to a solution of 3.61 g. (0.0207 mole) of methanesulfonic anhydride in 25 ml. of dry acetonitrile at 10° C. The mixture

was allowed to stand overnight at 10° C. then evaporated at 55-60° C. under reduced pressure. The product, the methanesulfonic acid salt of 2-dibenzylaminoethyl methanesulfonate was obtained in 94% yield. It was 91-93% pure.

Example XI

The reaction of Example X was carried out but substituting 50 cc. of dry ethyl ether for the acetonitrile. The product of Example X was obtained but in reduced yield.

Example XII

The reaction of Example X was carried out but substituting 50 cc. of dry chloroform for the acetonitrile. The product of Example X was obtained but in reduced yield.

Example XIII

N-ethyl-N-(α -naphthylmethyl)-2-aminoethyl chloride hydrochloride, 2.84 g. (0.01 mole) and silver methanesulfonate, 4.06 g. (0.02 mole) were dissolved in 75 ml. of dry acetonitrile. The solution was heated to refluxing with stirring for 3 hours then filtered and evaporated at 55-60° C. under reduced pressure. The residue, the methanesulfonic acid salt of N-ethyl-N-(α -naphthylmethyl)-2-aminoethyl methanesulfonate was obtained in 94% yield. It was 91% pure.

Example XIV

Methanesulfonic anhydride, 3.02 g. (0.0173 mole) was dissolved in 50 ml. of dry benzene. A solution of 3.97 g. (0.0173 mole) of N-ethyl-N-(α -naphthylmethyl)-2-aminoethanol in 25 ml. of dry benzene was added. A viscous second layer began to separate after about 10 minutes. The mixture was allowed to stand overnight. The benzene then was evaporated at 55-60° C. under reduced pressure and the residue dried to constant weight at 60° C. and 1 mm. pressure. The product, the methanesulfonic acid salt of N-ethyl-N-(α -naphthylmethyl)-2-aminoethyl methanesulfonate was obtained in 68% yield. It was 63% pure.

Example XV

By substituting the chemically equivalent quantity of silver ethanesulfonate for the silver methanesulfonate of Example XIII and following the procedure of Example XIII, the ethanesulfonic acid salt of N-ethyl-N-(α -naphthylmethyl)-2-aminoethyl ethanesulfonate was obtained in 90% yield. It was 88% pure.

Example XVI

By substituting the chemically equivalent quantity of N-ethyl-N-(9-fluorenyl)-2-aminoethyl chloride hydrochloride for the 2-dibenzylaminoethyl chloride hydrochloride of Example I and following the procedure of Example I, the methanesulfonic acid salt of N-ethyl-N-(9-fluorenyl)-2-aminoethyl methanesulfonate was obtained in a yield of 97%. The product was 95% pure. It crystallized on triturating with 50% propylene glycol.

Example XVII

Methanesulfonic anhydride, 3.45 g. (0.0198 mole) was dissolved in 25 ml. of dry acetonitrile. A solution of 5.00 g. (0.0198 mole) of N-ethyl-N-(9-fluorenyl)-2-aminoethanol in 25 ml. of dry acetonitrile was added dropwise with stirring. The clear solution was allowed to stand at room temperature for 17 hours. The white crystalline product then was isolated by fractional precipitation with absolute ether. It was purified by dissolving in absolute methanol at room temperature, diluting the solution to incipient cloudiness with absolute ether and chilling in the refrigerator. The purified product, the methanesulfonic acid salt of N-ethyl-N-(9-fluorenyl)-2-aminoethyl methanesulfonate, melted at 157-159° C.

Anal.—Calcd. for $C_{18}H_{21}O_3NS \cdot CH_4O_3S$: C, 53.37; H, 5.90; N, 3.28. Found: C, 53.54; H, 5.99; N, 3.25.

The product assayed 100.6% by titration against sodium thiosulfate.

Example XVIII

By substituting the chemically equivalent quantity of N-benzyl-N-phenoxyethyl-2-aminoethyl chloride hydrochloride for the 2-dibenzylaminoethyl chloride hydrochloride of Example I, following the procedure of Example I except that the reaction mixture was refluxed for 2 hours instead of 3 hours, the methanesulfonic acid salt of N-benzyl-N-phenoxyethyl-2-aminoethyl methanesulfonate was obtained in 92% yield. It was 88.5% pure.

Example XIX

By substituting the chemically equivalent quantity of N-ethyl-N-(α -benzylphenoxyethyl)-2-aminoethyl chloride hydrochloride for the 2-dibenzylaminoethyl chloride hydrochloride of Example I and following the procedure of Example I, the methanesulfonic acid salt of N-ethyl-N-(α -benzylphenoxyethyl)-2-aminoethyl methanesulfonate was obtained in the form of an opalescent syrup in 86% yield. It was 80% pure.

Example XX

By substituting the chemically equivalent quantity of N-benzyl-N-(1-phenyl-2-propyl)-2-aminoethyl chloride hydrochloride for the dibenzylaminoethyl chloride hydrochloride of Example I and following the procedure of Example I, the methanesulfonic acid salt of N-benzyl-N-(1-phenyl-2-propyl)-2-aminoethyl methanesulfonate was obtained in the form of an opalescent resin in 97% yield. The product was 94% pure.

Other examples of the invention will be apparent from a consideration of the compounds represented to be therapeutically effective in the above mentioned article by Nickerson and Gump, using those compounds as starting materials and carrying out the reactions of the above examples.

When the above identified procedure, using sodium thiosulfate, was carried out to determine the relative rates of formation of the cyclized ion, the following results were obtained.

Time required for reaction to proceed 75% to completion.

R'	R''	X	Temp., °C.	Time (minutes)
benzyl	benzyl	Cl	25	98
Do	do	CH_3SO_3	5	26
Do	do	$C_2H_5SO_3$	5	23
α -naphthylmethyl	ethyl	Cl	25	23
Do	do	$C_2H_5SO_3$	5	7

It will be noted that the rates of reaction of the esters were measured at 5° C. while the rates of reaction of the chlorides were measured at 25° C. Since the velocity constant of a homogeneous reaction is approximately doubled or trebled for a 10° C. rise in temperature, the difference in reactivity between a sulfonic acid ester and its corresponding chloride is much greater than is apparent from the above table. (Glasstone, Textbook of Physical Chemistry, D. Van Nostrand, New York (1940), page 1067.)

As has been noted above, the unexpectedly rapid rate of cyclization of the sulfonic acid esters of the present invention is of particular value when the compounds are used therapeutically, because of the physiological response they elicit.

It will be noted that the product obtained from carrying out the reactions set forth above, is the salt of the same sulfonic acid which is involved in the ester linkage. It will be appreciated from what has been set forth above, that a primary feature of the invention resides in the sulfonic acid ester structure of the compound and that the acid that forms the salt of the compound is relatively important. Thus, although the compounds obtained in the above examples have as the salt-forming acid the same acid that occurs in the ester, the invention contemplates

salts of other acids such as the hydrochloric, sulfuric, and other sulfonic acids, as well as carboxylic acids. The free base can be prepared from this salt by neutralization with one equivalent of an alkali, but in most instances this free base is not stable.

Mention may also be made of the fact that some of the sulfonic acid esters of the invention possess antithistaminic properties to a degree greater than the corresponding chlorides. Thus, the present invention brings about potentiation in this added respect.

What is claimed is:

1. Compounds having the general formula

wherein R' is selected from the class consisting of lower alkyl, aralkyl and aryloxyalkyl radicals and R is selected from the class consisting of lower alkyl, phenyl, lower alkyl substituted phenyl, and benzyl radicals.

2. Compounds having the general formula

wherein R is a lower alkyl radical.

3. Compounds having the general formula

wherein R is a lower alkyl radical.

4. The methanesulfonic acid salt of N-ethyl-N-(o-benzylphenoxyethyl)-2-aminoethyl methanesulfonate.

10

5

5. The methanesulfonic acid salt of N-benzyl-N-(phenoxethyl)-2-aminoethyl methanesulfonate.

6. The process for obtaining sulfonic acid esters of 2-dialkylamino-ethanols in which a compound having the formula:

in which R' and R'' are selected from the class consisting of lower alkyl, aralkyl and aryloxyalkyl radicals, the selected radicals containing between them at least one benzene ring which is linked to the nitrogen through at least one and no more than two aliphatic carbon atoms, is mixed with a compound having the formula:

20 in which R is selected from the group consisting of: a lower alkyl, a phenyl and a benzyl radical; in the presence of a non-hydroxyl solvent.
